UNITED STATES PATENT OFFICE.

WILLIAM LANGE, OF TOMKINS COVE, NEW YORK, ASSIGNOR OF ONE-HALF TO
CALVIN TOMKINS, OF NEW YORK, N. Y.

SCREENING-TRAY FOR STONE WASHERS AND SEPARATORS.

1,079,133.

Specification of Letters Patent.

Patented Nov. 18, 1913.

Application filed July 31, 1913. Serial No. 782,243.

To all whom it may concern:

Be it known that I, WILLIAM LANGE, a citizen of the United States of America, and a resident of Tomkins Cove, in the county of Rockland and State of New York, have invented certain new and useful Improvements in Screening-Trays for Stone Washers and Separators, of which the following is a description.

10 My invention relates to the screening trays used, in the rotating drums of stone washers and separators, for the purpose of separating larger and smaller particles of stone from sand, mud, dirt, and other impurities, according to the method and with the apparatus shown and described in my prior application for patent filed April 4, 1913, and serially numbered 758,803, and the object of my invention is to produce screening trays of an improved construction and capable of performing the functions attributed to the screens or trays referred to in the aforesaid application.

25 In the drawings forming a part of the present specification Figure 1 is a front or face view of a washer drum provided with screening trays in accordance with my present invention. Fig. 2 is an edge view of the same. Fig. 3 is a view of a screening tray 30 and a fragment of the washer drum, the view being taken from within the washer drum and looking to the right as indicated by the arrow marked "3" in Fig. 1. Fig. 4 is a front view of a screening tray detached 35 from the washer drum, in the direction indicated by the arrow marked "4" in Fig. 3.

40 In performing its functions of washing and separating, the washer drum is rotated in the direction of the arrow A, in Fig. 1, the screening trays receiving a mixture from a chute extending in the direction of the arrow B and delivering the mixture to the screening trays approximately at the point C. The revolution of the washer drum carries the mixture on the course indicated by the arrow D, the screening trays, as they change position, losing the fluid and waste material and retaining the screened material, the fine screened material being delivered 45 in the direction of the arrow E and the coarse screened material being delivered in the direction of the arrow F, the screened material being afterward deposited through the front orifice into suitable receptacles not 50 shown, and the waste material passing

through the rear orifice all as described in my hereinbefore mentioned application.

55 10 is the front plate of the washer drum, 11 the peripheral casing of the washer drum, 12 the rear wall of the washer drum, 13 and 14 the front and rear roller guides, 15 the front or screened material orifice and 16 the rear or waste material orifice, the wall about the front orifice being stiffened by an annular band 17 and the wall about the rear orifice being stiffened by an annular band 18 carrying an annular flange or lip 19. All of these parts are approximately of the construction shown in my hereinbefore referred to application.

70 Within the washer drum a circular series of screening trays 20 is removably or permanently secured, the trays being alike one to the others. Each screening tray is composed of a perforated plate 21 which is stiffened by angle irons 22, extending approximately lengthwise of the screening tray, and which is provided with numerous perforations 23 preferably in the form of rows of staggered slots extending transversely of the screening tray, and with a backturned lip 24 along its inner end, and an imperforate plate 25 extending lengthwise of the screening tray, and spaced from the perforated plate 21 except along its lower and inner edges, 80 the lower edge of the imperforate plate being bound to the lower edge of the perforated plate and to the brackets 26 by the fastenings 27, the brackets 26 being secured to the front plate 10 and the peripheral casing 11 of the washer drum by fastenings 28 and 29 respectively, the upper part of each perforated plate 21 being additionally secured in position by brackets 30 and fastenings 31, to the peripheral casing 11. The 85 inner edge of the imperforate plate is provided with a backturned lip 32 corresponding in shape to the backturned lip 24 of the perforated plate 21, and the backturned lip 32 seats in or against the rear side of the 90 backturned lip 24 making a fluid deflecting inner edge to the screening tray.

95 The perforated plates are preferably bent or curved into a scoop shape for the better retention of the mixture being screened but 105 this curving is a matter of choice and its benefit will vary with the speed and material with which the washer drum is used or employed.

110 The longitudinal angle irons tend to di-

rect the mixture toward the axis of the washer drum and prevent a congestion of the screened material on any part of the perforated plate 21 or side shifting of the material to the lower edges of the screening trays.

The transverse slots or perforations 23 pass the fluid portions of the mixture through the screening tray and their transverse arrangement has been found to be preferable, from a practical standpoint, to a longitudinal arrangement, the perforations being also preferably long and narrow, and varying in size with the material to be screened, and staggered or overlapped.

The imperforate plates 25 may be longitudinally or transversely curved but should flare outwardly away from the perforated plates 21 from the lower edge up. The imperforate plates receive the rush of fluid from the perforated plates and prevent it being deposited on succeeding screening trays thus preventing drenching of such succeeding screening trays and permitting them to screen their share of the mixture without interference. The imperforate plate further directs the fluid toward the axis of the washer drum where the fluid can be either of further service in the washing operation or may be permitted to escape over the flange or lip 19. The backturned lips 24 and 32 direct the fluid backward at the inner edges of the screening trays thus preventing the fluid from escaping with the screened material through the front orifice 15.

Having thus described my invention the following is what I claim as new therein and desire to secure by Letters Patent:

40 1. A screening tray constructed with a perforated plate having a back turned lip along its inner end and an imperforate plate extending lengthwise of the perforated plate from its lower and inner edges and spaced from the perforated plate beyond said edges.

45 2. A screening tray constructed with a plate having transverse perforations and a back turned lip along its inner edge and an imperforate plate extending lengthwise of the perforated plate from its lower and inner edges and spaced from the perforated plate beyond said edges.

50 3. A screening tray constructed with a plate having transverse staggered perforations and a back turned lip along its inner

edge and an imperforate plate extending lengthwise of the perforated plate from its lower and inner edges and spaced from the perforated plate beyond said edges.

4. A screening tray constructed with a plate having transverse rows of staggered slots and a back turned lip along its inner edge and an imperforate plate extending lengthwise of the perforated plate from its lower and inner edges and spaced from the perforated plate beyond said edges.

5. A screening tray constructed with a perforated plate having a back turned lip along its inner edge and longitudinal stiffening bars, and an imperforate plate extending lengthwise of the perforated plate from its lower and inner edges and spaced from the perforated plate beyond said edges.

6. A screening tray constructed with a perforated plate having a back turned lip along its inner end, and an imperforate plate extending lengthwise of the perforated plate from its lower and inner edges, spaced from the perforated plate beyond said edges and having a back turned lip along its inner end.

7. The combination with a drum, of a screening tray constructed with a perforated plate having a back turned lip along its inner end, and an imperforate plate extending lengthwise of the perforated plate from its lower and inner edges, and spaced from the perforated plate beyond said edges and means for securing the tray in non-radial position within the drum.

8. A screening tray constructed with a curved or scoop shaped perforated plate having a back turned lip along its inner end, and an imperforate plate extending lengthwise of the perforated plate from its lower and inner edges, and spaced from the perforated plate beyond said edges.

9. A screening tray constructed with a curved or scoop shaped perforated plate having a back turned lip along its inner end, and an imperforate plate extending lengthwise of the perforated plate from its lower and inner edges, spaced from the perforated plate beyond said edges and having a back turned lip fitting against the back turned lip of the perforated plate.

WILLIAM LANGE.
